PRINTING MECHANISM FOR AUTOMATIC
POLARISCOPESOtto Paul Walter Bernhardt, Woodland, Calif.,
assignor to Spreckels Sugar Company, San
Francisco, Calif., a corporation of California

Application October 23, 1950, Serial No. 191,684

5 Claims. (Cl. 101—93)

1

My invention relates to printing mechanisms; and particularly to a printing mechanism useful in conjunction with the photoelectric apparatus described and claimed in Patent No. 2,503,808, of which I am a joint inventor.

One of the important objects of my invention is the provision of a printing mechanism that will accurately indicate and record in terms of percentage the quantity of optically active substance such as sugar in a solution, the quantity of which is proportional to the light rotatory power of the substance as measured by photometric apparatus balanced by photoelectric means.

Another object of my invention is the provision of such a printing mechanism in which the indicia bearing printing disk is brought to a balanced value indicating position by automatic means.

Still another object of my invention is the provision of a printing mechanism in which the indicia on the disk are inked simultaneously with the insertion of a tare ticket into printing position; and in which electrically operated means, controlled by the placing of the ticket in printing position, operate to press the ticket against the indicia on the disk to record on the ticket the value indicated.

My invention possesses other objects and features of value, some of which, with the foregoing, will be set forth in the following description of my invention. It is to be understood that I do not limit myself to the showing made by the said description, and the drawings, as I may adopt variant forms of my invention within the scope of the appended claims.

Referring to the drawings: Fig. 1 is a plan view of the printing mechanism of my invention together with its mechanical inter-connection with the balancing lever and phase-sensitive balancing motor of the photoelectric automatically balancing polariscope. Fig. 1-A is a continuation of Fig. 1 on Sheet #2 of the drawings and showing the pivotal connection at the other end of the balancing lever. The scale of Figs. 1 and 1-A is approximately half-size.

Fig. 2 is a vertical sectional view taken in the plane indicated by the line 2—2 of Fig. 1; and Fig. 3 is a vertical section taken in the plane indicated by the line 3—3 of Fig. 2. Fig. 4 is a vertical sectional view taken in the same plane as Fig. 3 but with the platen in its uppermost position; and Fig. 5 is a diagrammatic view showing the electrical circuit of the printing mechanism; and Fig. 6 is a fragmentary bottom view showing the indicia on the underside of the printing disk and arcuate plate.

2

Broadly, the ticket printing mechanism of my invention comprises a main frame composed of spaced parallel plates on one of which is rotatably mounted suitable indicia printing means. A phase-sensitive motor, common to the printing mechanism and to a photoelectric automatically balancing polariscope, is utilized to rotate the indicia means to a position determined by the intensity of electrical impulses induced in a phototube by light passing through the optical system of the polariscope. The printing disk is rotatable to a position which will indicate the percentage of sugar in a sample solution. Means are also provided for placing a tare ticket to be printed in printing position. This is accomplished by providing a second frame slidable on the main frame. With the ticket in place, the manually initiated movement of the second frame acts to simultaneously apply ink to the indicia, place the ticket in position to be printed, and trip a switch controlling the movement of an electrically operated platen which presses the ticket against the indicia. A spring then effects the recovery movement of the second frame.

In greater detail and referring now to the drawings, the ticket printing mechanism of my invention includes a main frame having a top plate 2 and a base plate 3, the plates being held in spaced parallelism by tubular posts 4. The plates are conveniently rectangular in shape, with the posts positioned adjacent the corners and held by screws 6.

Rigidly mounted on the base plate 3 is a bearing stud 7, held by a nut 8 on the reduced end 9, extending through the base plate. At its upper end, the stud is reduced in a shaft portion 12, seated in an aperture in the top plate to further insure its rigid mounting.

Means are provided for printing a tare ticket with indicia representing the percentage of sugar in a sample of syrup. These include a printing disk 13 bearing indicia 14 on its underside and which is fixedly connected for rotation with the driven pulley 15 by a screw 16 threaded into the pulley through the disk. Both disk and pulley are journaled on the fixed shaft constituting the upper portion 12 of the stud 7, so that there is slight clearance between the upper face of the disk and the under side of the top plate 2.

In order that a base or zero point may be established correlated to the value or percentage of sugar in a sample solution as indicated by the indicia on the printing disk, an indicia bearing arcuate plate 17 is provided. The arcuate plate is a lateral extension contiguous to the disk edge,

and is mounted on the arm 18, interposed in the space provided between the printing disk and the top plate. A thumb nut 19 threaded to a stud 21, rigidly mounted on the arm and extending upwardly through the arcuate slot 22 in the top plate, controls the setting of the zero point on the arcuate plate to a position opposite the zero point as indicated on the top surface of the printing disk. When this condition exists, the zero point on the underside of the disk is exactly opposite the evaluating indicia pointer 23 on the underside of the arcuate plate; and the printing mechanism may be considered to be synchronized with the photoelectric automatically balancing polariscope.

In order that the function of the correlated printing disk and indicia bearing arcuate plate shall be clear, it is pertinent to explain at this point the driving means for my printing mechanism as used in conjunction with the photoelectric apparatus as described and claimed in Patent No. 2,503,803.

As has been described and claimed in that patent, a phase-sensitive reversible motor is utilized for balancing the photoelectric apparatus. The operation is based on the fact that in a Lipisch double field polarizer, the incident light receives a different treatment in the two halves of the field insofar as the plane of polarization in one half of the field differs from that of the other half by a small angle, generally called the half-shadow angle. When the analyzer is so oriented that its plane of polarization essentially bisects the half-shadow angle, the halves of the field transmit the same amount of light and the field appears evenly illuminated. When a substance of rotatory power, such as a concentrated sugar solution, is placed between the polarizer and analyzer, the halves of the field no longer appear equally bright. A movement of the quartz compensator wedge in the proper direction then again restores the field to balance. In the automatically balancing polariscope of the patent referred to, a revolving semi-circular shutter scans the field continuously at a rate of 3600 revolutions per minute. Thus, in the case of an unbalanced field, the intensity of the light reaching the phototube varies between a minimum and a maximum. The current passed by the anode of the phototube varies with the intensity of the light; and since this occurs 3600 times per minute the phototube and the amplifier connected thereto produce a 60 cycle alternating current. The rotating shutter is so positioned that the resultant alternating current is always either 90° or 270° out of phase with the main line alternating current, depending on which side of the field is darker.

The combination of main line alternating current and that produced by the amplifier causes the balancing phase-sensitive motor to operate. The rotation is either clockwise or counter-clockwise, depending on the direction of unbalance. The mechanical connections are so arranged that the quartz compensator is always driven toward the point of balance. When the balance point is reached no more alternating current reaches the balancing motor from the amplifier and it no longer moves the quartz compensator. My printing mechanism is coupled to the compensator so that at the balance point, the percentage of sugar in the sample solution, which has been introduced into the sample chamber is evaluated by the rotation of the printing disk away from the base or zero pointer 23. This value may be

transferred to a tare ticket by the manipulation of suitable mechanism.

The mechanical linkage connecting my printing mechanism in synchronism with the automatically balancing polariscope comprises a stiff steel lever 26, pivotally mounted at one end by pin 27 on a slide block 28 arranged in the slideway 29 and adjustable by screw 31. The slideway is fixedly mounted on the same base (not shown) which supports the plate 3 of the printing mechanism.

At the other end, the lever is pivotally mounted by pin 34 on the slide block 36, the pin extending through a slot 37 in the lever to permit slight longitudinal movement of the lever. The block is slidably arranged in a slideway 38, which like the slideway 29 is fixed on the same base with the printing mechanism.

Movement of the slide block and pivot pin, and consequently of the lever 26, is effected by a tempered steel wire 39, looped about and fixed to the pulley 15 on the printing mechanism; and extending around the driving pulley 41. The latter pulley is driven by the belt 42 from the phase-sensitive motor 43. Preferably, the wire 39 is dead-ended on the pulley 15 and held under high mechanical tension by screws 44 in the flanges of the pulley 15.

In order to insure that rotational movement of the motor will result in corresponding movement of the slide block and pivot pin, and consequently of the lever 26, one reach of the steel wire 39 is securely fastened to the slide block by a clamp 46 held in place by screws 47. It is apparent therefor, that rotation of the motor results in rotation of the printing disk to a value indicating position; and that the rotation is proportional to movement of the slide block and lever, which in turn move the compensator which again in turn, through the action of the phototube, controls the motor.

The quartz compensator is affected by the movement of the lever through the following means. Interposed between the ends of the lever 26 and spaced a short distance from the pivot 27 is a third pivotal connection. This comprises a slide block 48 supported in a slideway 49. A pivot pin 51 on the block extends upwardly through the slot 52 in the lever. It is the function of this slide block to adjust the position of the quartz compensator of the apparatus in a direction which will tend to equalize the intensity of light emitted from both halves of the field, and thereby balance the apparatus. Movement of the slide block 36 by the balancing motor results in a proportionately smaller movement of the slide block 48 and of the balancing quartz compensator, which is connected thereto. The proportionality of this movement is adjustable through the screw positioned slide block 28. Preferably, lost motion in the mechanical linkage is prevented through the use of tapered spring-loaded pivots and precision dovetail slides throughout.

Means are provided for transferring the percentage of sugar in the sample solution, as indicated on the disk, to a tare ticket.

A frame 56 mounted on the underside of the top plate 2, is folded over upon itself to provide a pocket 57, in which a tare ticket may be supported. The front end of the frame has a handle 58, and its rear end at the fold is formed with a rectangular recess 59. The frame is also provided with parallel slide rods 61 slidably arranged

in spaced brackets 62 secured to the top plate by screws 63.

At their extreme ends, each of the rods is connected to a bracket by a tension spring 64. As can be seen in Figs. 1, 3 and 4, the springs work against manual pressure applied to the frame tending to place the ticket in position to be printed, and restore the frame to its position shown in Figs. 1 and 3, from the position shown in Fig. 4.

Ink is applied to the indicia on the printing disk and arcuate plate by an ink saturated fabric roller 65 journaled on a shaft 66 supported on lugs 67 mounted on the frame 56, so as to position the roller immediately behind the pocket 57. As the operator pushes in on the frame in which a ticket has been placed, the roller moves toward the indicia, applying ink as it passes thereunder. The parts are so proportioned and arranged that when the roller has cleared the indicia, that part of the ticket which lies within the recess is directly under the indicia and in position to be printed.

When the frame reaches this position, means mounted on the frame has initiated the operation of mechanism to press the ticket against the indicia. A laterally extending arm 68 is pivotally mounted at one end on the underside of the ticket supporting frame by a pivot bolt 69 set in the bracket 70, rigidly depending from the frame. At its other end the arm is provided with a shoe 71 having a rearwardly extending arm 72 and a forwardly extending arm 73. As the frame moves away from the operator to place the ticket in position to be printed, the arm 72 strikes the actuating lever 74 of the micro-switch 75. Movement of the lever closes the circuit between the main line and the solenoid 76, which is mounted on a cross bar 77 secured to the base plate 3 by screws 78. The energized solenoid propels the platen 79 upwardly, striking the underside of the ticket and pressing it against the indicia.

Projecting from one side of the platen is a lug 80. As the platen moves upwardly propelled by the solenoid, the lug contacts the arm 73, lifting the arm 72 clear of the micro-switch lever. This breaks the circuit and allows the platen to return to its position as shown in Figs. 2 and 3.

Contact of the lug 80 with the arm 73 is effected at a time when the platen is just short of being at its uppermost position; and it is left to momentum to carry the platen to the top. A rubber pad 81 on the platen absorbs some of the shock as the platen strikes the ticket and disk, and also acts as a resilient bumper to propel the platen downward. Gravity also assists in restoring the platen to its lower position.

The operator now releases the frame, and the springs 64 return it to the position shown in Figs. 1 and 3; the printed ticket is withdrawn and the printing mechanism is ready for another cycle.

In ordinary laboratory practice the percentage of sugar content in a sample solution is generally read to within one-tenth of one percent. In my printing mechanism, the graduations on the printing disk are conveniently in steps of one-tenth of one percent, and the reading of the zero point on the arcuate plate 17 is customarily to the nearest graduation, that is, to the nearest one-tenth of one percent. If greater accuracy is desired, the exact position of the zero point may be estimated to one one-hundredths of one percent. With my printing mechanism, polarizations may be read and printed at the rate of one every 75

nine seconds or approximately 400 samples per hour.

I claim:

1. In a ticket printing mechanism of the character described, a frame having a pair of spaced parallel plates, an indicia bearing printing disk rotatably mounted on one of the plates and adjacent the other plate, indicia bearing means adjacent the printing disk and interposed between the disk and said other plate for correlation with said indicia bearing printing disk, means slidably mounted on said other plate for supporting the ticket to be printed, roller means mounted on the ticket supporting means for applying ink to the printing disk and indicia bearing means, a platen movably supported on said first mentioned plate and underlying the unprinted ticket, automatically controlled motor means for rotating the printing disk to a value indicating position, electrical means mounted on said first mentioned plate for operating the platen to press the ticket against the indicia of the printing disk and indicia bearing means, and manually operated switch means arranged on said first mentioned plate for controlling said electrical means.

2. In a ticket printing mechanism of the character described, a frame having a top plate and a bottom plate, an indicia bearing printing disk rotatably interposed between said top and bottom plates, an indicia bearing arcuate plate disposed circumferentially adjacent the printing disk and pivotally adjustable adjacent the top plate for correlation with the indicia bearing printing disk, a second frame slidably mounted on the top plate for supporting the ticket to be printed, roller means mounted on said second frame for applying ink to said printing disk and said arcuate plate, a platen movably supported on the bottom plate and underlying the unprinted ticket, automatically controlled motor means for rotating said printing disk to a value indicating position, electrical means mounted on said bottom plate for operating said platen to press the ticket against the printing disk and said arcuate plate, and manually operated switch means arranged on the bottom plate and controlled by movement of said second frame for controlling said electrical means.

3. In a ticket printing mechanism of the character described, a frame having a pair of spaced parallel plates, an indicia bearing printing disk rotatably mounted on one of the plates and adjacent the other plate, an indicia bearing arcuate plate circumferentially disposed adjacent the printing disk and pivotally adjustable adjacent the other said plate for correlation with the indicia bearing printing disk when the latter has been rotated to a position indicating values to be recorded, means slidably mounted on said other plate for supporting the ticket to be printed, roller means mounted on the ticket supporting means for applying ink to the printing disk and indicia bearing means, a platen movably supported on said first mentioned plate and underlying the unprinted ticket, automatically controlled motor means for rotating the printing disk to a value indicating position, electrical means mounted on said first mentioned plate for operating the platen to press the ticket against the indicia of the printing disk and arcuate plate, and manually operated switch means arranged on said first mentioned plate for controlling said electrical means.

4. In a ticket printing mechanism of the character described, a frame having a pair of spaced parallel plates, a printing disk bearing indicia

mounted on one of the plates and adjacent the other plate and rotatable to a position indicating values to be recorded, indicia bearing means adjacent the printing disk and interposed between the disk and said other plate for correlation with said indicia bearing printing disk, means slidably mounted on said other plate for supporting the ticket to be printed, roller means mounted on the ticket supporting means for applying ink to the printing disk and indicia bearing means after the two have been correlated to indicate values to be recorded, a platen movably supported on said first mentioned plate and underlying the unprinted ticket, automatically controlled motor means for rotating the printing disk to a value indicating position, electrical means mounted on said first mentioned plate for operating the platen to press the ticket against the indicia of the printing disk and indicia bearing means, and manually operated switch means arranged on said first mentioned plate for controlling said electrical means.

5. A ticket printing mechanism including a frame having a top plate and a bottom plate, a printing disk bearing indicia mounted on the bottom plate and adjacent the top plate and rotatable to a position indicating values to be recorded, motor means for rotating said printing disk to said value indicating position, an indicia bearing arcuate plate mounted on the frame contiguous to the disk edge and pivotally adjustable about the rotational axis of the printing disk, the indicia of each said printing disk and arcuate plate being correlated to the other when the disk has reached

its value indicating position, a second frame slidably mounted on the top plate for supporting the ticket to be printed, roller means mounted on said second frame for applying ink to said printing disk and arcuate plate coincident with movement of the second frame to place the ticket in position to be printed, a platen movably supported on the bottom plate and underlying the ticket, electrical means mounted on said bottom plate for operating said platen to press the ticket against the printing disk and said arcuate plate, and manually operated switch means arranged on the bottom plate and controlled by said movement of the second frame for controlling said electrical means.

10 15 OTTO PAUL WALTER BERNHARDT.
